UNITED STATES PATENT OFFICE.

JOHN R. STARCK, OF WEEHAWKEN, NEW JERSEY.

SEPARABLE FASTENER.

Application filed August 24, 1922. Serial No. 584,113.

To all whom it may concern:

Be it known that I, JOHN R. STARCK, a citizen of the United States, and a resident of Weehawken, in the county of Hudson and the State of New Jersey, have invented a new and Improved Separable Fastener, of which the following is a full, clear, and exact description.

The present invention relates to new and useful improvements in separable fasteners, and it pertains more particularly to a jewelry clasp of the type employed on wrist-watch bands, bracelets and similar articles for personal wear.

It is one of the primary objects of the present invention to provide a separable fastener for articles of this character for which a positive fastening between the two members is had.

It is a further object of the invention to provide a clasp of this character which may be longer lived than are clasps of this type as generally constructed.

It is a still further object of the invention to provide a clasp of this character which is simple in operation.

With the above and other objects in view, reference is had to the accompanying drawings, in which—

Figure 1 is a top plan view of a clasp constructed in accordance with the present invention, said clasp being shown in its closed position;

Fig. 2 is a detail plan view of one member of the clasp;

Fig. 3 is a detail plan view of the other member of the clasp;

Fig. 4 is a detail sectional view taken on the line 4—4 of Fig. 1;

Fig. 5 is a detail view of a slightly modified form of the invention.

Referring more particularly to the drawings, the device comprises two members 11 and 12 adapted to be attached each to its respective end of a band 13, which forms the wrist-watch band, bracelet, or other article of apparel to which the clasp may be attached. The member 11 comprises a bar or plate of sheet metal provided with slots 14, by means of which it is attached to the article of apparel and said slots form the main bar or plate with a body portion 15 which in turn is provided with head members 16 of which there are two shown in the drawings. It is obvious, however, that the number of head members 16 may be increased or

diminished to meet the requirement of the clasp.

The member 12 is in the form of a plate provided with a slot 17, by means of which the article of apparel 13 is attached and said plate is cut out to provide a suitable ornamental design 18. With the ornamental design 18 and preferably forming a part thereof is a plurality of spaced fingers 19, said fingers being of a resilient nature. There is one pair of these fingers for each of the head members 16 carried by the member 11, and the description of one set of said fingers therefore will suffice. The spring fingers 19 are each formed from the metal of the member 12 and said fingers are rigidly connected to the metal member 12 as at 20, by being formed integral therewith. These fingers 19 lie in spaced relation one to the other and converge slightly toward each other as indicated by the reference character 21. At one end of the fingers the space between the two is enlarged as indicated by the reference character 22 and is circular in form of a size to permit of the free insertion of its respective head member 16. At the opposite end of the fingers, said fingers are spaced as indicated by the reference character 23 and are curved as indicated by the reference character 24 to receive the shanks 25 of their respective head members 16, as shown in Fig. 4. The space between the spring fingers 19 slightly in advance of the curved portion 24 thereof, is less than the diameter of the shank 25 in order that as the shank passes through the space between the fingers, the fingers will be sprung outwardly to permit the shank to enter the curved portions 24 thereof.

This form of the invention operates as follows:

The head members 16 are inserted in the enlarged portions 22 of the space between the fingers 19 and the shanks 25 of the head members are moved through the space between the fingers 19 until the shanks pass into the curved portions 24 of said fingers. Just before the shanks pass into the curved portions 24, due to the converging disposition of the fingers 19, a binding action will be exerted upon the shanks 25 and will spring the fingers 19 to permit of the shanks passing into said curved portions 24. As soon as the shanks enter the curved portions 24, the fingers spring back to normal position and prevent accidental displace-

ment of the shanks with respect to their respective curved portions thereof and thus retain the shanks in their respective curved portions.

5 In that form of the invention shown in Fig. 5, the member 12 is formed with spring fingers 30 spaced with relation to each other and said fingers are so formed that the space therebetween is enlarged at one end as at 31. The inner edge of these fingers 30 is curved as at 32 to provide a contracted throat portion 33 through which the shanks pass in the securing together of the two members of the fastener. This contracted throat portion prevents accidental displacement of the shanks of the head members with respect to the space between the fingers 30, it being understood, however, that the shanks of the head members may be moved therethrough to disengage the two parts of the clasp.

From the foregoing it is apparent that the present invention provides a new and improved form of separable fastener especially adapted for use in connection with

articles of jewelry in which the members of the fastener are securely held against accidental displacement, and, at the same time, owing to their resilient construction and the fact that they are not placed under a great amount of strain during the fastening and unfastening of the clasp members, said clasp is long-lived and durable.

What is claimed is:

A separable fastener comprising a plurality of head members, a plate on which said head members are mounted, shanks spacing said head members from said plate, a second plate, a plurality of fingers formed in said second-mentioned plate and arranged in pairs, the fingers in each pair being spaced, and having their opposed edges alternately converging and diverging, and a shank receiving portion formed on the end of each of said fingers, the free extremity of each of said fingers being unattached to permit of resilient action of the shank receiving portions.

JOHN R. STARCK.
